INVENTOR

FRANK WIBERLEY

BY Chas. C. Gill

ATTORNEY

UNITED STATES PATENT OFFICE.

FRANK WIBERLEY, OF JAMAICA, NEW YORK, ASSIGNOR TO BARTHELS MANUFACTURING COMPANY, OF GLENDALE, NEW YORK, A CORPORATION OF NEW YORK.

WEARING-APPAREL.

1,396,799.

Specification of Letters Patent. Patented Nov. 15, 1921.

Application filed July 1, 1919. Serial No. 308,038.

To all whom it may concern:

Be it known that I, FRANK WIBERLEY, a citizen of the United States, and a resident of Jamaica, in the county of Queens and 5 State of New York, have invented certain new and useful Improvements in Wearing-Apparel, of which the following is a specification.

The invention pertains more particularly 10 to what I designate as a button-hole strip to be applied to garments at one edge portion thereof which is to be buttoned to an adjacent portion carrying buttons, whereby the garment may be closed.

One object of the invention is to avoid 15 the necessity of working button-holes in a garment, and I preferably accomplish this result by providing a strip having loops, and which strip may be sewed to the edge 20 portion of the garment in such position that the loops may be engaged with the customary buttons and serve as button-holes. The strip of my invention will preferably 25 be of two-ply inclosing a lining, the parts being suitably fastened together at the outer edge of the strip and initially left open at the opposite edge thereof so that the strip may receive between its plies the edge portion 30 of the garment to which the strip is to be applied. On the lining or on the inner 35 ply of the strip will be fastened certain novel loops whose outer ends, serving as button-holes, are projected through eyelet holes in the inner ply of the strip in convenient position to be concealed and to be engaged 40 with buttons. The loops are of special character in that each is in one integral piece of woven tape folded over upon itself and comprising two thin flat end portions and 45 an intermediate portion, constituting the loop proper, which is round or circular in cross-section. The two flat ends of the tape are utilized as means whereby the folded over tape may be conveniently sewed to the 50 button-hole strip and not leave an unsightly projection or thickness, and the intermediate circular portion of the tape serves as a button-hole to be engaged with a button.

The invention will be fully understood 55 from the detailed description hereinafter presented, reference being had to the accompanying drawings, in which:

Figure 1 is an elevation of a button-hole strip embodying my invention, the inner ply 55 of the strip being shown as turned out-

wardly to expose the flat ends of the button-hole tapes where they are sewed to the lining of the strip;

Fig. 2 is a transverse section, on a larger scale, through the same, taken about on the 60 dotted line 2-2 of Fig. 1;

Fig. 3 is a corresponding view of the same and illustrates the fact that the button-hole tape may be drawn outwardly through 65 the inner ply of the strip when applying the loop thereof on a button, after which the loop may be retracted inwardly or to its normal position, shown in Fig. 2;

Fig. 4 is an elevation of the tape before 70 being folded over to create the button-hole loop, and

Fig. 5 is a perspective view of the same, the tape being shown as having been folded over preparatory to the flat ends being superimposed and sewed to the fabric of the 75 strip.

In the drawings, 10 designates the button-hole strip as a whole, 11 the inner ply thereof, 12 the outer ply of said strip, 13 a lining or concealed ply, 14 inner strips serving 80 as a filling at the outer edge of the main strip 10, and 15 a line of stitching by means of which the plies 11, 12, lining 13 and strips 14 are sewed together. Preferably 85 the strips 14 are integral with the plies 11, 12 and lining 13 and formed by folding inwardly the outer edge portions of said parts, whereby there are left no raw edges at the outer edge of the main strip 10. The strips or layers 14 are shown as being three in 90 number and they afford a very durable outer edge portion to the strip 10.

The button-hole tapes are numbered as a 95 whole 16 and these tapes are preferably sewed to the lining 13 by two lines of stitching 17, but they may be independently secured to the lining 13 or to any portion of the fabric or strip 10 by sewing or otherwise. The button-hole tapes 16 are each 100 in one integral piece and comprise two thin flat end portions 18 and an intermediate loop portion 19 which is circular in cross-section and serves as a button-hole to engage a button. In the preferred construction 105 of the button-hole strip 10 the flat end portions of the button-hole tapes are secured to the lining 13, and the loop portions 19 of said tapes are projected through eyelet holes 20 in the inner ply 11 of the strip 10, as I illustrate in Fig. 1, said loop portions 110

19 being concealed by the strip 10, but exposed sufficiently to be engaged on buttons on the opposite edge of the garment employing at one edge the strip 10. The flat end 5 portions 18 of the button-hole tapes may be more or less superimposed on each other, as I illustrate in Fig. 1, and then sewed to the strip 10 by the stitches 17 or otherwise, as may be preferred.

10 The button-hole tapes are manufactured by weaving strong threads together to produce both the thin flat ends 18 and the round or cord-like reduced intermediate portion 19, and hence said tapes and the button-holes 15 or loops they provide are very strong and durable. The button-hole tapes 16 may be very quickly and conveniently applied to the fabric of the strip 10, and they are obviously quite inexpensive and serve as a 20 desirable substitute for the working of button-holes along one edge of the garment to be attached to an opposite edge thereof carrying buttons. I preferably secure together the outer edges of the plies or layers of the 25 strip 10 by the stitching 15 and leave the other edges of the layers of said strip unconnected or open, as shown in Figs. 2 and 3, so that the strip may receive between its plies the edge portion of a garment, to which 30 the strip will be sewed and serve as a substitute for the working of button-holes in the garment. The strip 10 when applied to a garment will afford, by means of the loops 19, suitable button-holes for buttons at an 35 adjoining edge of the garment and said strip 10 serves to conceal the loops 19 and also the buttons to be engaged by them.

By securing the flat ends of the button-hole loops to the lining 13 and projecting 40 the loops 19 through the eyelet holes 20, said loops 19 may, when applying the same to buttons, be drawn outwardly from between the plies of the strip to a suitable extent to be conveniently engaged with the buttons, 45 as I represent in Fig. 3. When a loop has been drawn outwardly, as shown in Fig. 3, and applied upon a button and then the garment is tightened on the body, the loop will be retracted inwardly to its initial position, shown in Fig. 2. The button-hole 50 loops by being fastened to a yielding lining 13 thus become adjustable for convenience in applying the same on buttons, and one benefit of this construction is that by 55 reason thereof the loops themselves do not have to be unduly large and may be applied to fairly large-sized buttons. When the loops 19 are pulled outwardly, as shown in Fig. 3, they may be applied over buttons of 60 large size and then when retracted inwardly to the position shown in Figs. 1 and 2, said loops snugly encompass the shank of the button or the threads by which the button may be fastened to a garment. The loops 19 65 may also be drawn outwardly for conven-

ience in detaching them from buttons of large size.

What I claim as my invention and desire to secure by Letters Patent, is:

1. A button-hole strip for the edge of a 70 garment having buttons at opposite edge thereof, said strip comprising inner and outer plies of fabric sewed together at the outer edge of the strip and initially open at the other edge of the strip to receive the 75 fabric of the garment and be secured thereto, and a series of independent button-hole tapes secured by sewing between said plies and affording loops to be used as a substitute for button-holes, said loops being projected 80 through said inner ply back from the edge of the strip and concealed by the outer face of the strip, and said button-hole tapes each being an integral woven piece of tape folded upon itself and having ends woven flat for 85 attachment to the strip, and an intermediate portion woven circular in cross-section affording the loop to engage the button.

2. A button-hole strip for the edge of a 90 garment having buttons at the opposite edge thereof, said strip comprising inner and outer fabric plies and a fabric lining and all secured together by sewing at the outer edge of the strip, and a series of independent button-hole tapes secured by sewing to said lining 95 and affording loops to be used as a substitute for button-holes, said loops being projected through the inner ply back from the edge of the strip and concealed by the outer face of the strip, and said button-hole tapes each being an integral woven piece of tape folded upon itself and having ends woven flat for attachment to said lining and an intermediate portion woven circular in cross-section and affording the loop to engage the button. 105

3. A button-hole strip for the edge of garments having buttons at the opposite edge thereof, said strip comprising inner and outer plies of fabric folded inwardly and sewed together at the outer edge thereof 110 so as to present a finished edge, and a series of independent button-hole tapes secured by sewing between said plies and affording loops to be used as a substitute for button-holes, said loops being projected through 115 said inner ply back from the edge of the strip and concealed by the face of the strip, and said button-hole tapes each being an integral woven piece of tape folded upon itself and having ends woven flat for attachment to the strip, and an intermediate portion woven circular in cross-section affording the loop to engage the button. 120

4. A button-hole strip for application to 125 garments having buttons for fastening parts of the garment together, said strip having a series of independent button-hole tapes secured by sewing thereto and affording loops to be used as a substitute for button-holes for said buttons, said button-hole 130

tapes each being an integral woven piece of
tape folded upon itself and having ends
woven flat for attachment to the strip and
an intermediate portion woven circular in
5 cross section affording the loop to engage
the button.

Signed at Jamaica, in the county of

Queens, and State of New York, this 24th
day of June, A. D. 1919.

FRANK WIBERLEY.
